UNITED STATES PATENT OFFICE

2,436,610

BODY GARMENT

Hilarie Eitel Saxon, Seattle, Wash.

Application January 8, 1946, Serial No. 639,821

6 Claims. (Cl. 2—80)

1

This invention relates to body garments and, more particularly, to a garment construction suitable for use in playsuits, bathing suits, trunks with and without a bib, pajamas, slacks, and the like. Still more particularly, this invention relates to the provision of a garment adapted to encase the hip portion of the torso and to be openable and, at the same time, form-fitting.

It is an important object of this invention to provide a garment which is simple to construct, easy to fit to a relatively wide range of body sizes, insuring in all instances a relatively close fit and which may be easily loosened for donning or removal.

Another object of my invention is to provide a body garment having a double-layered portion with reversible parts.

Still another object of my invention is to provide, in body garments, a construction which will insure a close fit in the crotch area.

The foregoing object and others ancillary thereto I prefer to accomplish as follows:

According to a preferred embodiment of my invention I provide, in connection with a smooth main panel of a body garment, a pair of overlapping opposite panels attached to a relatively narrow crotch-tab adjacent a common plane, each to an opposite side of such plane from the other. Specifically, the garment is provided with two overlapping rear panels that are integral with the side edges of a front panel and are otherwise unattached to each other except through their mutual attachment to a crotch strap extending rearward from the front panel. The attachment of the rear panels to the crotch strap may be either internal or external, and when each is attached to its own side of the median line, the rear panels can be reversed to determine which is going to overlap outwardly of the other. With this arrangement the garment is suitable for children, teen-age girls, or adults. In garments such as trunks, playsuits, pajamas and the like, it serves as a simple arrangement for smoothly and reversibly closing such garments about the body. If the rear panels are joined to the crotch-tab overlapped on the median, reversibility is obviated.

The novel features that I consider characteristic of my invention are set forth with particularity in the appended claims. The invention itself, however, both as to its organization and its method of operation, together with additional objects and advantages thereof, will best be understood from the following description of a specific em-

2

bodiment when read in connection with the accompanying drawings, in which:

Fig. 1 is a front view of a garment included in my invention;

Fig. 2 is a rear view of the garment in Fig. 1;

Fig. 3 is an interior fragmentary view of the crotch as seen from the plane suggested by line 3—3 of Fig. 2;

Fig. 4 is a rear fragmentary view of a modified form of my invention; and

Fig. 5 is a fragmentary interior view of the crotch as seen from the plane in line 5—5 from Fig. 4.

The preferred embodiment of my invention is shown in Figs. 1, 2, and 3, in which the invention is incorporated in a playsuit comprising the front panel 10, above which rises bib 12 that merges into shoulder straps 14, 15, having respectively tie strings 16 and 17, which may be either knotted behind the neck, as suggested in Fig. 2, or brought downward across the back of the wearer and thence secured adjacent the waist.

The front panel 10 has lower converging tapered edges 18 and 19, between the lower edges of 25 which is the crotch-tab 20. As shown in Fig. 3, the tab 20 preferably flares from its narrowest mid-portion to a relatively wider rear end 21. The side edges 24 and 25 of the front panel are each joined to a rear panel designated 26 and 30 27 respectively. The rear panels may be integral with the front panel or there may be a seam along the side edges 24 and 25, depending upon the manner in which the garment-maker may wish to produce this construction to derive the best economy of material and labor.

In Figs. 2 and 3 appears the line M—M which is an upright median through the garment. Each of the rear panels 26 and 27 has an overlapping flap portion 28 and 29 respectively that is roughly 40 triangular and which extends across and overlies the median M—M. The flaps 28 and 29 are relatively horizontal along the waist line and curve from the waist generally across the median where they are attached to the crotch-tab 20, each to the respective side of the median on which the panel joins the front panel.

In a preferred form of the construction as shown in Fig. 3, the lower pointed portions of the rear panels can be seen to be attached, rearward 50 of the lateral median L—L, to the tab 20.

In one form of my construction as can be seen in Fig. 2, the rear panels 26 and 27 at the corners of the flaps 28 and 29 are provided with ties 30 and 31 which may be brought forwardly across the 55 hips and around the waist and tied or otherwise

joined to secure the garment into close fitting overlapping relation across the buttocks. Keepers are indicated at 32 and 33 to insure that the ties 30 and 31 are held upward to the waist at the rear of the garment.

In Figs. 2 and 3 the rear panels 26 and 27 are attached to the outer face of the tab 20, and the tab extension 21 lies inward and under the less overlapping portions of the rear panels 26 and 27 to serve as a shield and to prevent exposure if the rear panels should be strained so as to tend to gap adjacent the crotch.

In Figs. 4 and 5 the front panel 40 has a crotch-tab 41, to the inner surface of which is attached the rear panels 42 and 43. In this case the lower pointed portions of the rear panels are each attached wholly to its respective side of the median M'-M', and have been carried slightly farther forward than was the case in connection with the garment in Fig. 3. This is possible because these point ends lie inside of the crotch-tab 44 and thus a slightly thicker crotch is obtainable. As described before, the crotch tab 44 overlies the slightly overlapped lower pointed ends of the rear panels and serves as a shield, however, from the outside rather than, as before, on the inside of the garment.

This overlapping arrangement of the rear panels 26 and 27, and 42 and 43, insures in a garment that there is adequate material across the rear to form cups that will accommodate either a slim-hipped or a full-hipped body, since there is a wide latitude of adjustment. In the case of a slim-hipped person the rear panels overlap to a greater degree than otherwise.

It will be noted that, between the lower edges of the front panel 10 and the rear panels, suitable oblique leg openings are provided. By proper cutting these openings are shaped and positioned to fit the body closely near the crotch, yet as scantily as possible. The various panel edges shown throughout the drawings have been indicated as being bound with tape, but it will be obvious that the edges may be merely hemmed or otherwise treated according to the many practices in the art.

While I have shown and described particular embodiments of my invention, it will occur to those skilled in the art that various changes and modifications may be made without departing from the invention, and I, therefore, aim in the appended claims to cover all such changes and modifications as fall within the true spirit and scope of my invention.

Having thus described my invention, I claim:

1. A play suit, comprising: a front panel to cover the body from hip to hip and from the crotch upward, said front panel merging with breast-covering portions, a tab to extend substantially through the crotch, a rear panel attached to each hip side-portion of the front panel and to the crotch tab adjacent a medial line thereof, said rear panels being of a size to overlap upward from adjacent their point of attachment to the crotch tab, and means for securing the rear panels in overlapped adjusted relation across the rear of a wearer.

5. A play suit comprising: a front panel to cover the body from hip to hip and from the crotch upward, said front panel merging with breast-covering portions, a tab to extend substantially through the crotch, a rear panel attached to each hip side-portion of the front panel and to the inner face of the crotch tab adjacent a medial line thereof, said rear panels being of a size to overlap upward from adjacent their point of attachment to the crotch tab, and means for securing the rear panels in overlapped adjusted relation across the rear of a wearer.

10. A play suit, comprising: a front panel to cover the body from hip to hip and from the crotch upward, said front panel merging with breast-covering portions, a tab to extend substantially through the crotch, a rear panel attached to each hip side-portion of the front panel and to the outer face of the crotch tab adjacent a medial line thereof, said rear panels being of a size to overlap upward from adjacent their point of attachment to the crotch tab, and means for securing the rear panels in overlapped adjusted relation across the rear of a wearer.

15. A garment for the hips and lower torso, comprising: a front panel including a tab to extend substantially through the crotch, a rear panel attached to each side of the front panel and to said crotch tab adjacent a medial line, said rear panels being of a size to overlap upward from adjacent their point of attachment to the crotch tab, and means for securing the rear panels in overlapped adjusted relation across the rear of a wearer.

20. A garment for the hips and lower torso, comprising: a front panel including a tab to extend substantially through the crotch, a rear panel attached to each side of the front panel and to the inner face of said crotch tab adjacent a medial line, said rear panels being of a size to overlap upward from adjacent their point of attachment to the crotch tab, and means for securing the overlapped rear panels in adjusted relation across the rear of a wearer.

25. A garment for the hips and lower torso, comprising: a front panel including a tab to extend substantially through the crotch, a rear panel attached to each side of the front panel and to the outer face of said crotch tab adjacent a medial line, said rear panels being of a size to overlap upward from adjacent their point of attachment to the crotch tab, and means for securing the overlapped rear panels in adjusted relation across the rear of a wearer.

30. HILARIE EITEL SAXON.
